A. P. K. Peck

United States Patent Office.

JACOB B. HOUGH, OF LEBANON, OHIO, ASSIGNOR TO HIMSELF AND
SAMUEL BRADEN, OF THE SAME PLACE.

Letters Patent No. 62,957, dated March 19, 1867.

IMPROVEMENT IN DOUBLE-TREES.

The Schedule referred to in these Letters Patent and making part of the same.

TO ALL WHOM IT MAY CONCERN:

Be it known that I, JACOB B. HOUGH, of Lebanon, in the county of Warren, in the State of Ohio, have invented certain new and useful Improvements in Double-Trees; and I do hereby declare that the following is a full and exact description thereof, reference being had to the accompanying drawings, and to the letters of reference marked thereon.

The drawing represents a top or plan view of my improved double-tree as used upon a common wagon-tongue.

The nature of my invention consists in the arrangement of a curved fulcrum-block and guide-rods, or their equivalents, in combination with a double-tree, in such a manner as to vary the point of draught, for the purpose and in the manner hereinafter described; also in the use of a stay-block in combination with the compensating double-tree and fulcrum-block, all of which will be fully described in this specification.

To enable others to make and use my invention, I will proceed to describe its construction and operation.

I construct my double-tree in the usual form, as indicated in the drawing by the letter D, and place it centrally upon the tongue and hounds A B C. In the upper side of the double-tree D there are two staples inserted, as seen at b b. E is the fulcrum-block, formed, as indicated in the drawing, with its rear face, against which the front edge of the double-tree works, curved in the arc of a circle. F is the stay-block, and is of the same thickness of the double-tree and the fulcrum-block, and these two blocks are firmly secured by bolts to the tongue and hounds. The double-tree is held in place by the curved rods a a, which are securely fastened to the blocks E and F, and pass through the staples b b, as shown in the drawing. Each end of double-tree D is provided with a single-tree in the usual manner, for attaching the horses to the wagon or carriage.

From the foregoing description it will be understood that in using my improved double-tree the changing point of draught will always correspond with the difference in power applied to the ends of the double-tree. In every instance and condition the double-tree will adjust itself upon the fulcrum-block in such a manner as to favor the less powerful horse, because, as the more powerful of the two will keep in advance of the other, the point of draught will correspondingly approach and remain in nearer proximity to the most advanced of the animals. In other words, the foremost horse will necessarily have the short end of the lever, while the rearmost will draw from the longer end. In the event of the entire suspension of power at one end of the double-tree, then the stay-block will operate to check and hold the double-tree from oscillating to any considerable extent, serving the purpose of stay-chains, which are generally required for the same purpose. There are other obvious advantages to be derived from the use of my invention, it being well adapted for breaking young animals to work. Its use is not limited to the wagon or carriage, but may be applied to a long clevis for the plough in the same manner that the parts are attached to the wagon. My improved double-tree are not only simple in construction, but much cheaper than any device of the kind that has been introduced to my observation.

Having now fully described the construction and manner of using my invention, what I claim, and desire to secure by Letters Patent, is—

1. The combination of the double-tree D with the fulcrum-block E and guides a a, constructed, arranged, and operating in the manner and for the purpose described.
2. I claim the stay-block F, in combination with the compensating double-tree and its fulcrum-block, arranged to operate conjointly with the guide-rods a a substantially as and for the purpose set forth.

In testimony whereof I have hereunto set my hand this 9th day of December, A. D. 1865.

J. B. HOUGH.
